PIN TRAY FOR METAL DESK CENTER DRAWERS

James V. Crell, Norwood, Ohio, assignor to The
Globe-Wernicke Co., Norwood, Ohio, a corpora-
tion of Ohio

Application February 13, 1947, Serial No. 728,217

13 Claims. (Cl. 45—7)

1

This invention relates to a pin tray or the like for the center drawer of a metal desk. Because when a desk drawer is rapidly closed, loose items in the desk tend to gravitate toward the back of the drawer where they are hard to reach, it has become customary in the trade to provide adjacent the front face of the drawer, a relatively narrow tray which may or may not be subdivided into compartments for the purpose of holding small articles to which ready access is desired. Such trays are usually used for pencils, paper clips, pins, rubber bands and the like. In order to permit the user to readily grasp objects in the tray, it is usually made of curved cross section.

The provision of pin trays in metal desks has been a rather difficult problem because the drawer and the tray are both of sheet metal and it is substantially impossible to make the tray integral or of the same piece of material as the drawer. Various expedients have been proposed whereby the tray is a separate element to be inserted in the drawer during assembly, but none of these has proved wholly satisfactory. Either the tray cannot later be removed from the drawer if desired, or else it is not firmly held in engagement with the drawer. Furthermore, the provision of partitions for the tray has presented a problem in fabrication.

With the above considerations in mind it is an object of my invention to provide a tray which is simple in construction and can therefore be easily fabricated. It is another object of my invention to provide a tray as outlined, which can easily and quickly be assembled to the drawer but which can with equal ease be removed from the drawer if necessary. A further object of my invention resides in the provision of simple partition elements, which can easily be assembled with the tray and the drawer and which when assembled are firmly held in position.

These and other objects of my invention which will be described in more detail hereinafter or which will be apparent to one skilled in the art upon reading these specifications, I accomplish by that certain construction and arrangement of parts of which I shall now describe an exemplary embodiment.

Reference is made to the drawing forming a part hereof and in which:

2

Fig. 1 is a plan view of a drawer provided with a tray according to my invention.

Fig. 2 is a front elevational view of the same.

Fig. 3 is a side elevation of the same.

5 Fig. 4 is a cross sectional view taken on the line 4—4 of Fig. 1, showing the tray in position.

Fig. 5 is a view similar to Fig. 4 showing the manner in which the tray is assembled to the drawer.

10 Fig. 6 is a fragmentary view similar to Fig. 1 with the tray removed.

Fig. 7 is a perspective view of one of the tray partition elements.

15 Briefly in the practice of my invention, I provide a metal drawer having the usual configuration including a front wall and top flange. The top flange terminates in a small down turned flange. The bottom of the tray is provided with

20 a strip providing a flange spaced from the bottom, and the tray, which is of generally J-shaped cross section, has portions engaging behind the down turned flange and under the bottom flange. The tray may be slotted perpendicularly to the

25 axis of the drawer and partition members of substantially rectangular configuration are inserted in the slots from below to constitute dividers for the tray. In Figs. 1, 2, and 3, I have shown a metal desk tray having a bottom 10,

30 front wall 11, and top flange 12. Since the drawer itself does not constitute a part of my invention, it will not be described in detail, except to say that it is provided with the usual runners 13, and may be provided with a lock 14, as is well known.

35 As most clearly seen in Figs. 4 and 5 the top flange 12 terminates in a down turned flange portion 15. The conventional rear face of a drawer front wall is omitted, because the pin tray takes its place.

40 To the bottom of the drawer 10, there is fastened as by spot welding a strip 16 having a cross section, best seen in Fig. 5. It is a generally Z-shaped and provides a flange 17 spaced from the bottom 10 of the drawer. Preferably also it extends substantially the full width of the drawer, so that it will have the advantage of preventing small cards and papers from sliding under the pin tray and becoming caught, or in the case of small cards, from be-

45 coming lost.

The tray itself is indicated at 18 and is generally J-shaped in cross section. At the top it is provided with a portion 19 to fit under the flange 10 and has the off set portion 20 to engage behind the flange 15. The hook portion of the J designated at 21 is bent downwardly providing a smooth curve of small radius at 22 and provides a second substantially J-shaped element reversely disposed to the aforementioned J-shaped configuration. The hook portion 23 of the second J-shaped portion is preferably angular, and its terminal flange 24 is of such height as to fit snugly under the flange 17.

The structure in its assembled form is such that it cannot be accidentally dislodged and yet the tray may be readily removed by taking the drawer out of the desk and holding it in a substantially vertical plane with the lock portion up and dropping it a few inches to the floor. The slight jarring thus produced will dislodge the tray, so that it may be removed from the drawer.

Partitions for the tray are usually desirable and by my construction partitions can readily be provided. The portion 21 is slotted perpendicularly to the axis of the tray in as many places as partitions are desired. The slots are best seen in Figs. 4 and 5 and terminating at 25 and 26.

The partition members, best seen in Figs. 4, 5, and 7 are substantially rectangular and are provided with a cutaway portion at 27 to leave the finger 28. The finger 28 is shorter by the thickness of the metal from which the tray is made, so that when the portion 29 of the partition rests on the bottom, there will be room for a thickness of metal between the bottom of the drawer and the finger 28.

The partitions are slipped upwardly from beneath into the slots and the finger 28 of each is engaged within the hook portion 23 of the tray. When the tray is assembled in the drawer, as seen in Fig. 4, the partition members are securely held against displacement. They are longer than the distance between the points 25 and 26, so that they cannot be swung upwardly through the slots and they cannot slip forward, because of the finger 28 being engaged by the hook portion 23.

At points where partitions are to be provided, it is, of course, necessary to cut out the flange 17 as indicated at 29 in Fig. 6. The cutaway portion 27 permits the clearance of the strip 16, so that the portion 29 can rest on the drawer bottom.

It will be seen that I have provided an exceedingly simple tray construction in which the tray replaces a wall normally required in the drawer and which can readily be assembled and disassembled in relation to the drawer.

Numerous modifications will suggest themselves to those skilled in the art and for this reason I do not intend to limit myself in any manner, except as set forth in the claims which follow.

Having now fully described my invention, what I claim as new and desire to secure by Letters Patent is:

1. In a metal desk center drawer having a front wall, a top flange extending rearwardly therefrom, and a flange extending downwardly from the latter, a pin tray extending substantially the width of said drawer, said tray being substantially J-shaped in cross-section and having an element along its upper edge adapted to engage behind said downwardly extending flange,

said tray having a wall extending downwardly from the hook portion of said J and inturned at the bottom, and said drawer having a flange spaced from the bottom thereof parallel to said drawer front, the inturned portion of said tray being adapted to be held under said drawer flange.

2. A structure according to claim 1, in which said tray is partially slotted normal to its axis, and in which a partition member is retained in said slot.

3. A structure according to claim 2, in which said partition member is of a height to be substantially held against the bottom of said drawer by the ends of said slot, and is of a length greater than the length of said slot.

4. A structure according to claim 3, in which said partition member has a portion cut away to clear said drawer flange.

5. In a metal desk center drawer having a front wall, a top flange extending rearwardly therefrom, and a flange extending downwardly from the latter, a pin tray extending substantially the width of said drawer, said tray being substantially J-shaped in cross-section and having an element along its upper edge adapted to engage behind said downwardly extending flange, said tray having a wall extending downwardly from the hook portion of said J and inturned at the bottom, and said drawer having a substantially Z-shaped element fastened to the bottom thereof to provide a flange spaced from said bottom and extending substantially the width of said drawer, the inturned portion of said tray adapted to be held under said drawer flange.

6. A structure according to claim 5, in which said tray is partially slotted normal to its axis, and in which a partition member is retained in said slot.

7. A structure according to claim 6, in which said partition member is of a height to be substantially held against the bottom of said drawer by the ends of said slot, and is of a length greater than the length of said slot.

8. A structure according to claim 7, in which said partition member has a portion cut away to clear said drawer flange.

9. In a metal desk center drawer having a front wall, a top flange extending rearwardly therefrom, and a flange extending downwardly from the latter, a pin tray extending substantially the width of said drawer, said tray being substantially J-shaped in cross-section and having an element along its upper edge adapted to engage behind said downwardly extending flange, said tray having a wall extending downwardly from the hook portion of said J, and constituting in cross-section a second J-shaped cross-section reversely disposed, and said drawer having a substantially Z-shaped element fastened to the bottom thereof to provide a flange spaced from said bottom and extending substantially the width of said drawer, the hook portion of said second J-shaped portion being adapted to be held under said drawer flange.

10. A structure according to claim 9, in which said tray is partially slotted normal to its axis, and in which a partition member is retained in said slot.

11. A structure according to claim 10, in which said partition member is of a height to be substantially held against the bottom of said drawer by the ends of said slot, and is of a length greater than the length of said slot.

12. A structure according to claim 11, in which said partition member has a portion cut away to clear said drawer flange.

13. A structure according to claim 12, in which said partition member is provided with a finger portion of a size and shape to engage in the hook portion of said second J-shaped portion, and said drawer flange is cut away to accommodate said finger portion.
